UNITED STATES PATENT OFFICE.

DAVID D. JONES, OF SAN FRANCISCO, CALIFORNIA.

CLOTHES-HANGER.

1,037,487.

Specification of Letters Patent. Patented Sept. 3, 1912.

Application filed May 9, 1912. Serial No. 696,144.

To all whom it may concern:

Be it known that I, DAVID D. JONES, a citizen of the United States, residing in the city and county of San Francisco and State 5 of California, have invented certain new and useful Improvements in Clothes-Hangers, of which the following is a specification.

My invention relates to the class of 10 clothes-hangers especially adapted by reason of their construction to be set up within a room, and therein adjusted to the available space, and to be conveniently operated by being lowered to enable the clothes to be 15 easily hung and then raised up out of the way.

The object of my invention is to provide 20 a simple structure of this character, one which can be made at low cost and sold for a small price and which can be readily set 25 up and knocked down, and which in use will be firm and rigid and can be elevated without interference, to the full height possible in the apartment in which it is located.

To this end my invention consists in the 30 novel construction of the hanger which I shall now fully describe, by reference to the accompanying drawings in which the figure is a perspective view of my clothes-hanger.

1 is the main member of a frame. This, 35 in its best form, is longitudinally extensible in order to adjust it to the space available in the room. For this purpose it is made in two sections, as shown, one section being 40 slidably on the other by means of stirrups 2, secured to one section and in which the other section slides.

3 are the cross members of the frame. 45 One of these is removably fitted to one of the sections of the main member by a stirrup 4 and the other is similarly fitted to the other section of the main member by a stirrup 5, said stirrups being controlled as to position by stops 6. On these cross members 3 are the guides 7 through which is passed back and forth the clothes-line 8. In 50 order to steady this frame and yet avoid any interference with its capability of being hoisted as high as the room in which it is placed will permit, I fit one end of the main member 1 with the steadyng leg 9. This, as shown, extends downwardly or depends from the main member and is removably fitted thereto by means of a stirrup 10 secured to the upper end of said leg and into 55 which the end of the main member fits. To

this steadyng leg 9 are secured eyes 11 which are fitted to slide upon a fixed vertical rail 12, the disposition of the eyes being such that the leg is well held to the rail and 60 moves strictly parallel therewith, thereby steadyng the frame and holding it horizontal, so that it will not rock or tip under unequally disposed weight.

In apartments wherein it may be permitted, the rail 12 may be directly secured to the walls or between the floor and ceiling of the room and the hoisting devices may be similarly secured to walls or ceiling, but in houses where this would be prohibited, I 70 provide two end posts 13. These posts are secured to the floor 14 of the room 15, by means of brackets 16 screwed to the floor. To one of these posts the rail 12 is secured, as shown. To a fixed fastening 17 at the 75 top of the other posts 13 is secured one end of the hoisting line 18. The line thence extends down to and passes through a sheave 19 on the adjacent end of the main member 1. Thence the line extends longitudinally of the frame to and through a sheave 20 on the opposite end of said main member. Thence it passes up to and through a sheave 21 on the top of the first post 13, and thence the fall of the line hangs down and is adapt- 80 ed to be fastened to a cleat 22 on said post.

To operate the device it is first lowered to within convenient reach being there supported by the lower eye 11 of the steadyng leg 9 resting upon the lower fastened end of the rail 12, or if desired the leg 9 may rest on the floor. When the clothes are hung on the line 8, the hoisting line 18 is pulled upon, and the whole frame rises evenly and steadily on the rail 12 to the highest available level, there being nothing above the frame to interfere with its full elevation. In like manner it can be lowered again. It can be easily dismembered for removal from the room, and may as readily be set up 95 again.

Having thus described my invention what I claim as new and desire to secure by Letters Patent is—

1. A clothes-hanger comprising a frame 105 consisting of a main member and cross members secured to the ends of the main member; a clothes-line carried by and extending between the cross members; a steadyng leg secured to and depending from the end of the main member; a fixed vertical rail with 110 which said steadyng leg is slidably con-

nected; and hoisting mechanism for elevating and lowering said frame.

2. A clothes-hanger comprising a frame consisting of a main member formed of sections and stirrups in which said sections longitudinally slide, and end cross members with stirrups removably connecting them with the main member; a clothes-line carried by and extending between the cross members; a steadyng leg having a stirrup at its upper end by which it is removably fitted upon and is dependent from one end

of the main member; a fixed vertical rail with which said steadyng leg is slidably connected; and hoisting mechanism for elevating and lowering said frame.

In testimony whereof I have signed my name to this specification in the presence of two subscribing witnesses.

DAVID D. JONES.
